UNITED STATES PATENT OFFICE.

JOHN W. HYATT, OF NEWARK, NEW JERSEY.

SPRING-WINDING MACHINE.

1,289,453.

Specification of Letters Patent.

Patented Dec. 31, 1918.

Application filed January 4, 1918. Serial No. 210,247.

To all whom it may concern:

Be it known that I, JOHN W. HYATT, a citizen of the United States, of 141 Commerce street, Newark, county of Essex, and State of New Jersey, have invented certain new and useful Improvements in Spring-Winding Machines, fully described and represented in the following specification and the accompanying drawings, forming a part 10 of the same.

The present invention relates to a machine for winding a series of spiral wire springs with integral ties or connectors between their adjacent ends for use in a book-binding to form an elastic connection between the different leaves and signatures of the book.

To form such a series of spiral wire springs and connectors, the machine is provided with a mandrel which is alternately rotated and stopped by automatic means, and is rotated within a guide having a throat to lead in the wire and a slot through the guide longitudinal of the mandrel through which rolls press upon the sides of the coils as they are wound upon the mandrel, and each spring being advanced upon the mandrel when it is stopped, to draw out from the throat a straight portion of the wire which, 30 when the re-coiling is commenced, forms an integral connector with the succeeding spring.

An unbroken wire is fed to the mandrel during the winding of as many springs as 35 may be desired for use in a given book-binding, each spring when wound being advanced upon the mandrel and the series of springs severed from the wire when a suitable number of the springs has been completed.

40 The annexed drawing shows an embodiment of the invention, with rolls arranged to press upon the spring-coils at opposite sides of the mandrel during the winding of the spring, and means for retracting the rolls 45 during the advance movement of the spring.

The wire-guide is reciprocated by adjustable mechanism which may vary its stroke as desired, and is moved toward the chuck which drives the mandrel during the winding of one spring, and is moved an equal distance in a reverse direction when the spring is wound, so as to draw from the guide a suitable portion of the wire to form a connector with the succeeding spring.

The wire-guide is reciprocated continuously by connection to a continuously rotated cam, and such cam is connected by a clutch, with driving-gear, to intermittently rotate the rolls and the mandrel during the winding movement; and the clutch is automatically actuated to disengage the said driving-gear of the rolls from the cam after the winding of each spring, and to reengage the said driving-gear with the cam when the wire-connector has been formed and the 60 guide and rolls renew the winding movement.

The invention will be understood by reference to the annexed drawing, in which Figure 1 is a side elevation of the apparatus 70 with parts at the bottom broken for want of space; Fig. 1^a is a cross section on line $x-x$ in Fig. 1; Fig. 1^b is a cross section on the line $z-z$ in Fig. 1^c; Fig. 1^c is a vertical section of the guide through the center of the mandrel; Fig. 2 is a front elevation of the upper part of the machine; Fig. 3 is a plan of the operative ends of the roll-pressing levers with a section of the spring-guide above the level of the wire-inlet; Fig. 4 is a 80 plan of the gearing for driving the mandrel; Fig. 5 is a plan of the cutter; Fig. 6 is a plan of the top-plate with the same gearing as Fig. 4 and the clutch-disengaging device; Fig. 7 is an elevation of the upper part of the 85 machine partly in section where hatched at the center line of the driving-shaft; Fig. 8 is a plan of the top bed-plate with the parts for reciprocating the wire-guide; Fig. 9 is a plan of the roll-pressing levers with the 90 cam for working the same; Fig. 10 is a section through a book-binding employing connected spiral-springs; and Fig. 11 is a side view of a connected group of four springs 95 for such a binding. Figs. 3 and 4 are drawn upon a larger scale than the other figures.

The spiral-springs employed in a book-binding are very small, as shown in Fig. 11, where the spring is shown separate from the book, and in Fig. 10 extended through slanting holes s' at the hinge of the book S; and the strain upon all the parts of the machine is light, and it is therefore shown mounted upon a post A to which the bottom frame-plate B of the machine is secured, and to this a top-plate C is connected by tie-rods D.

A cam-shaft E is extended vertically

through the plates and carries a cam barrel F provided with three cams G, H and I. A driving-shaft J extends across the upper plate over the shaft E and is shown provided 5 with a driving-pulley J'. The driving-shaft is connected with the cam-barrel F by spur-gears F' and worm-gear F². The driving-shaft is connected by bevel-gears K and K' with a spindle L, which revolves in bearings 10 a in the opposite ends of a hollow shaft b which is mounted in bearings c in the frame-plates.

A hub d is attached to the hollow shaft and the bevel-gear K turns loosely thereon 15 and can be clutched thereto by any suitable clutch mechanism, as the particular construction of the clutch forms no part of the present invention.

As a means of operating the clutch, a 20 clutch-arm e is shown in Figs. 6 and 7, which is pressed normally by a spring e' in the direction of the arrow e², and when thus pressed, couples the bevel-gear K to the hollow shaft, and this shaft then rotates simultaneously with the cam-barrel F.

The cam I upon the upper end of the barrel F is provided to operate a lever l pivoted in a slot l' in the upper plate C, and having a lug c' at one end to engage the clutch-arm 30 e for a certain part of each rotation of the barrel and to thus release the hollow shaft from the gear-wheel K, which is rotated continuously by the driving-pulley J'.

A mandrel-chuck or driver o is mounted 35 rotatably in a bearing p upon the front edge of the top-plate C and the mandrel j extends parallel with the hollow shaft b.

Cam-levers m and m' are pivoted upon the hollow shaft opposite the upper and 40 lower ends of the barrel F, and have short arms m², as shown in Figs. 3 and 9, to carry the journals r, r' of the two winding-rolls h, h', which are pressed upon opposite sides of the spring-coils s when the cams are 45 operating upon the arms. The mandrel hangs between the rolls, and is rotated simultaneously therewith.

The hollow shaft b is connected by gear-wheels g with the journals r, r' of the 50 pressing-rolls h, h', such gears being indicated merely in dotted lines in Fig. 3, and a gear-wheel i upon the roll h drives a train of gears n which is connected to the mandrel-chuck o.

The gears n are indicated only by dotted 55 circles in Fig. 6, but where exposed in Fig. 4, are shown provided with the necessary teeth.

In this figure, the chuck of the mandrel 60 j is shown provided with a cog-wheel k which is connected with the gear-wheel i by the train of gears n.

The mandrel being very much smaller 65 than the pressing-rolls h, h', is rotated by the gearing n at a much higher rotary

speed than the rolls, so as to turn the surface of the winding-coils in unison with the surface of the rolls.

The spur-gears F' are, in practice, made removable, and change-wheels provided to 70 vary the ratio between the speed of the cam-barrel and the speed of the winding-rolls so as to wind a spring with a suitable number of coils before the cam I automatically actuates the clutch and arrests the mandrel 75 and rolls.

The wire v' is guided and laid upon the mandrel by a wire-guide having a body q provided with a longitudinal slot t intermediate to its ends for the passage of the 80 coiled springs. The guide has a head q' upon which a spool u is mounted, and the wire is led from the spool into the slot through a throat v. The guide is of rectangular section, as shown in Figs. 1^a and 1^b, 85 and is movable vertically in bearings t' and t². (See Fig. 1). The upper end of the guide above the slot is perforated for the passage of the mandrel which rotates therein, such perforation forming a bearing 90 which operates to center the mandrel in the slot in proximity to the throat v, and thus holds the mandrel firmly adjacent to the throat as the guide moves longitudinally upon the mandrel in coiling a spring. 95

The head q' projects above the throat v, and is perforated merely for the passage of the mandrel through the head to the said throat, below which the slot in the guide is wide enough to receive the finished springs, 100 which, when the required number has been wound with their intermediate connectors, are severed from the wire by cutters w shown in Figs. 1 and 5. The slot has covers t³ (Fig. 1^a) which are omitted in Fig. 1 105 to show the openings s.

The cutters are pivoted upon an arm M, (shown only in Figs. 1 and 2) adjustable upon the supporting post A so as to vary the distance of the cutter from the mandrel-chuck, as required by variations in the number and length of the springs in each integral series.

The cutters are pivoted like scissors blades, and the rear ends of their handles 115 or levers w' project at opposite sides of a drum m² having cam-projections x' to press the levers apart in opposition to a spring w³.

The drum has hollow journals M' carried in bearings upon the arm M, and is driven 120 by a shaft x² extended through the plate B of the frame, and connected by gears y with the barrel F, as shown in Fig. 1, so as to be actuated intermittently. The shaft is splined within the drum so as to drive the same in 125 whatever position the arm M may be adjusted upon the post.

During the winding operation, the coils cannot slip endwise upon the mandrel as they are pressed tightly thereon, and the 130

wire-guide is therefore moved toward the mandrel-chuck during the winding operation, by connection with a lever N, and the sloping cam-groove G on the barrel F.

5 The lever is provided with a variable fulcrum to enable the uniform throw of the cam to produce various strokes of the wire-guide, and has a slot o^2 in which the fulcrum can be adjusted.

10 The lever-pivot is a sleeve N' fitted to turn in an adjustable plate P which is movable in a slotted carrier P' attached to the under side of the frame-plate C by a foot P'.

15 The sleeve is clamped to the lever by a bolt and thumb-nut N^2 , when the lever and the plate P are adjusted.

The frame P' has scale-marks u' , and the plate has index-marks by which the plate 20 can be set in any adjusted position by the scale.

When the clamp-nut is tightened, the sleeve rocks with the lever in the plate P. The reciprocation of the guide may thus be 25 varied to suit the length of the spring-coils required in a single spring.

The cam revolves at a suitable speed to move the throat of the wire-guide at the same rate that the wire-coils accumulate 30 upon the mandrel, and through the automatic operation of the lever I and the clutch, the pressing-rolls are separated sufficiently to release the pressure upon the spring, when a sufficient number of the coils 35 have been wound, and the lever H has reached its extreme movement.

Each spring is wound during a portion 40 of the upward stroke of the guide, and the straight connector formed during the re-

When the movement is sufficient to carry the throat v to the upper end of the rolls, the guide passes between the roll-bearings m' as is apparent from Figs. 3 and 8, the 45 gear-wheels n being arranged wholly at the left-hand side of the guide so as to clear the same, as shown in Fig. 6.

The gear-wheel n' (which stands over the 50 guide) has no spindle, but runs on a stud, and thus permits the wire-guide to rise to the desired height.

By the adjustment of the fulcrum of the lever n, the guide is caused to move a space equal to the length of one of the springs s, 55 shown in Fig. 11, plus the intervening connector s', and such connector is formed between the successive springs in the following manner.

During the rise of the guide for a space 60 sufficient to wind one of the springs s the rolls and the mandrel are rotated, but when such spring is wholly wound the cam I comes into operation and disconnects the clutch from the gear K.

65 The cams H continue to press the rolls

tightly upon the wound coils, thus preventing any end movement of the coils while the guide q continues its upward movement.

During such upward movement the throat v draws a portion s' of the wire into the slot 70 t above the wound spring, and when the guide has reached its upper limit the cams H release the rolls h, h', which permits the loosening of the wound spring upon the mandrel and allows the descending movement of the wire-guide to push the spring and its connector s' downward. The rolls meanwhile remain stationary, and when the wire-guide reaches its lowest limit, the cams H and I operate simultaneously to press the 80 rolls toward the mandrel and to set the rolls and mandrel into rotation.

As the barrel F revolves continuously, the movement of the wire-guide is reciprocating, and as the coils, when the winding pressure is released, expand sufficiently to slip 85 upon the mandrel; the descending movement of the guide causes the wire which lies in the throat of the guide and attached to the last coil of the spring, to carry the wound 90 spring downward in the slot t of the guide.

One spring is wound during each rotation of the barrel F, and a series of springs is thus successively wound with integral connectors s', as shown in Fig. 11, and the series 95 is cut off by the cutters w, which are connected to the barrel F by gearing so proportioned as to sever the wire after the barrel has revolved a certain number of times. If desired, change-wheels may be connected to 100 the gears y to vary the operation of the cutter.

The holes formed in the leaves of the book to receive the springs are preferably inclined, as shown in Fig. 10, to admit a 105 spring longer than the thickness of the book, thus imparting more elasticity to the binding, and when the leaves for the book are prepared with the holes in a suitable position, the springs are threaded through the 110 same, as shown in Fig. 10, and the terminals of the springs engaged with the leaves of the book, by bending and clenching the same in the paper, or by any other suitable means.

Having thus set forth the nature of the 115 invention what is claimed herein is:

1. In a spring winding machine, the combination with a rotatable mandrel, of automatic means for intermittently rotating and stopping the mandrel, and means operating 120 automatically to alternately wind a series of close coils into a cylindrical spring upon the mandrel, and to shift such spring along the mandrel, when stopped, with a straight portion of the wire to form a tie with the suc- 125 ceeding spring.

2. In a spiral-spring winding machine, the combination, with a guide slotted longitudinally and having a throat at one side, of a mandrel rotated in the slot, means for ad- 130

vancing the guide longitudinally of the mandrel, means to feed the wire to the mandrel through the throat, and rolls arranged to press toward the opposite sides of the 5 mandrel and operating upon the coils of the springs through the sides of the slot.

3. In a spring-winding machine, the combination, with a mandrel, and a slotted guide for delivering wire thereto, of rolls arranged 10 to press upon the coils at opposite sides of the slot, means for advancing the guide longitudinally of the mandrel, and means for arresting the rotation of the rolls in the closing part of the advance movement, whereby 15 a portion of the wire is extended straight along the mandrel from the end of the spring to form an integral connector with a subsequently wound spring.

4. In a spring-winding machine, the combination, with a guide slotted intermediate 20 to its ends, of a passage in the upper end of the guide forming a bearing for a mandrel, a mandrel extended through such passage into the slot, means for reciprocating the 25 guide longitudinally of the mandrel, rolls arranged to press upon the spring-coil through the slot at opposite sides of the mandrel, means for rotating the rolls during the first part of the guide's advance movement, such rotation being continued during 30

the remainder of the movement to extend an integral tie from the wound spring, and means for retracting the rolls during the retracting movement of the guide.

5. In a spring-winding machine, the combination, with a mandrel and a slotted guide 35 for delivering a wire thereto and fitted to move longitudinally of the mandrel, of rolls arranged to press upon the spring-coils through the slot at opposite sides of the 40 mandrel, a cam rotated continuously and a lever connecting the said cam with the guide to reciprocate the said guide.

6. In a spring-winding machine, the combination, with a mandrel and a slotted guide 45 for delivering a wire thereto and fitted to move longitudinally of the mandrel, of rolls arranged to press upon the spring-coils at opposite sides of the mandrel, means for reciprocating the guide, means for rotating 50 the mandrel and the rolls, and cams operating synchronously to reciprocate the guide, to press the rolls upon the coils of the wound spring, and to arrest the movement of the rolls and mandrel when the spring is wound 55 to form an integral tie upon the spring.

In testimony whereof I have hereunto set my hand.

JOHN W. HYATT.
